UNITED STATES PATENT OFFICE.

WILLIAM M. HORTON, OF CLEVELAND, OHIO, ASSIGNOR TO THE ADAMS-BAGNALL ELECTRIC COMPANY, OF CLEVELAND, OHIO, A CORPORATION OF OHIO.

LAMP.

1,321,447.

Specification of Letters Patent. Patented Nov. 11, 1919.

Application filed September 18, 1917. Serial No. 191,909.

To all whom it may concern:

Be it known that I, WILLIAM M. HORTON, a citizen of the United States, residing at Cleveland, in the county of Cuyahoga and 5 State of Ohio, have invented certain new and useful Improvements in Lamps, of which the following is a specification.

This invention relates to headlights, an automobile headlight being shown herein, it 10 more particularly relating to an improved means for preventing the glare of said headlights, the object of the invention being to provide improved means for shifting the reflector of the headlight and maintaining it in 15 its shifted position.

The present invention is an improvement in part upon that shown and described in my contemporaneously pending application, Serial No. 134,625, filed December 2, 1916. 20 In that case an electrically operated means is used for shifting the reflector, which electrically operated means consists of a motor driven mechanism; and in the present case a substantially similar motor driven mechanism 25 is used for shifting the reflector. In my prior case, however, no provision was made for maintaining the reflector in its shifted position. In consequence there was nothing to prevent the user from so manipulating the reflector by keeping his finger 30 upon the push button or other switch as to immediately shift the reflector back into its normal position, and so throw the glare of the lamp into the eyes of the driver of an oncoming vehicle. The present improvement, however, is for the purpose of preventing this by making it impossible for the user to shift the reflector back into its normal position by continuing to press the shifting 35 button or switch. In other words, the present improvement provides a means which will shift the reflector from its normal position into a position to project the rays of light downward and maintain it in such position, notwithstanding the operator may continue 40 to press upon the reflector shifting button or switch, and until he has manipulated another button or switch.

In the present improvement, I have 45 accomplished this by providing in connection with the reflector shifting motor driven mechanism a breaker mechanism controlled by a button or switch in addition to the button or switch, which controls the reflector shifting mechanism, so that by the operation

of one button the reflector may be shifted, whereupon the current is broken and until both buttons are pushed, the reflector cannot be shifted back to its normal position to reflect the rays of light directly forward. In 60 practice, it has been found that where a single button is used to shift the reflector both downward and back to its normal position, some operators have a tendency at times to throw the light downward but 65 momentarily and then immediately shift it back, but this tendency is largely overcome when it is made necessary for the operator to operate another button in order to accomplish this.

Therefore the object of the present improvement is to provide broadly a means for shifting a reflector in connection with a means for maintaining or locking that reflector against further shiftable movement 75 and back to its normal position, and this by very simple, inexpensive and effective means.

In the drawings accompanying and forming a part of this specification,

Figure 1 is a plan view of a pair of headlights such as those usually used on automobiles with the reflectors connected for simultaneous movement, a part of each headlight being broken away to more clearly illustrate the improvement; Fig. 2 is a detail 80 view of one side of the motor driving mechanism; Fig. 3 is a front view of the motor driving mechanism shown in Fig. 2; Fig. 4 is a sectional detail view of the motor driven mechanism shown in Fig. 2; Fig. 5 is a diagrammatic view of the circuits; Fig. 6 is a front view of one of the lamps with a part of the reflector broken away to show the mechanism in the rear thereof; Fig. 7 is a vertical 85 sectional view of one of the lamps or headlights; Fig. 8 is a cross sectional view taken on line 8-8 and looking in the direction of the arrows of one of the lamps; Fig. 9 is a detail sectional view illustrating the present improved means for focusing the lamp. 90

Similar characters of reference indicate corresponding parts in the several figures of the drawings.

In the present improvement, each headlight comprises a casing 2 of any suitable 105 design or shape, having the usual lens or glass plate 3 carried by some suitable form of door 4. Within the casing, which is provided with a pair of diametrically opposed sleeves 5, the reflector 8 is mounted for shift- 110

able movement. In the present instance each reflector is shown provided with a strap 6 terminating at the forward or open end of the reflector at diametrically opposed sides 5 thereof in a U-shaped portion 7. These U-shaped portions receive the inner ends of the pivots for shiftably supporting each reflector in its casing. The reflectors are connected by a pair of coupling rods or pivots 10 37 coupled together by a coupling member 36, which rods 37 extend through the sleeves 5 of the lamp casings and into one end of each strap of a lamp, in which they are fixed, the opposite strap of each lamp being pivotally supported in a similar sleeve 5 by a short pivot rod.

From the foregoing it will be seen that on the movement of one reflector by the mechanism herein provided, both reflectors will be 20 likewise shifted, or either may be shifted manually by hand to properly bring the two reflectors into similar positions. The reflector is sleeved at its rear side as at 11 for the reception of the usual light bulb and socket 25 or connection, so that the light bulb of course moves with the reflector. In the present instance, the sleeve 70 is slit so as to form a spring clip 71 having an opening 71' at its forward end. The lamp bulb connector or sleeve 73 is provided with a series 30 of serrations or teeth 73' and between these teeth and the apertured spring clip is located a ball adapted to engage the teeth. By this means the lamp bulb may be shifted forwardly or backwardly in the sleeve 70 and maintained in its adjusted position by the locking ball 72 thereby to properly focus the bulb. Each casing is provided with an opening as at 12 for the reception of a suitable 40 connection, such as an Ediswan coupling or connector shown in the present instance as a double connector, one wire as 13 of which is attached to the bulb connector, and through the means of a suitable switch is connected 45 with the battery whereby the lights may be turned on and off as required. The other wire as 14, leads to the electrical operating means about to be described. Carried by the casing at any suitable point in the rear of 50 the reflector is a bracket 15 for supporting the actuating means for the reflector. Carried by this bracket is a suitable motor or electro-magnet 16 having a shiftable core 17 provided at its forward end with a contact 55 portion 18 and at its side with projecting pins 19. Also carried by the bracket at the forward side thereof, but insulated from the casing is a rigidly supported upstanding member 20 carrying a spring contact member or armature 21 having a contact portion 22 adapted to make or break contact with the contact portion 18 of the core. A short shaft 23 is supported for rotation at the upper end of the bracket 15, and for which 60 purpose the bracket 15 has secured thereto

a pair of forwardly extending sleeved portions 24. The short shaft extends through the lamp casing and by manipulating the end thereof, which projects through the casing the eccentric hereinafter described may 70 be operated manually. Between the sleeved portions 24 is located for oscillatory movement on the shaft a pair of oscillating arms 25, the lower ends of which are slotted for the pivots 19 of the core and between the 75 upper ends of these arms is located a pawl 27 in position to engage a ratchet wheel 26 rigidly secured to the short shaft 23. On the movement of the core back and forth the pawl will be operated through the medium 80 of the oscillating arms 25 thereby to rotate the ratchet wheel. The pawl is maintained in operative engagement with the ratchet wheel by a spring 30 secured to the bracket and the pawl, this spring being operative to 85 always return the core or plunger 17 to its forward position when it has been drawn to the rear or backward by the magnet. In other words, when the core or plunger 17 is drawn rearward or backward to break the 90 contact with the contact member 21, a spring 30 immediately acts through the pawl 27 to return the core or plunger into position to make contact so that when the mechanism is put in operation there is a continuous make 95 and break between the contact portions of the core 17 and the member 21 for the purpose about to be described. Located on one end of the shaft 23 is an eccentric 31 shown herein having a groove to receive a strap 32 100 to which is connected an actuating rod 33 by means of a screw 32'. The opposite end of this connecting rod 33 is connected to one of the reflectors as the left hand one shown in Fig. 1, preferably at the top thereof. Located within the vehicle are a pair of push buttons or switches A and B. One member of the push button A is connected with the electro-magnet 16 and also with one member as 61 of a spring contact, this spring contact member 61 having a projecting portion suitably secured to the bracket 15. The other member of this spring contact as 60 has a projecting portion suitably secured in position between the parts 20 and 21, and is connected with the other member of the push button A. These spring contact members 60 and 61 are properly insulated and the member 61 projects above the member 60 and into the path of a fiber roller secured either to the eccentric or to its shaft, and which fiber roller 62 constitutes a means for breaking contact between the spring contact members 60 and 61 at the proper time in the rotation of the eccentric shaft. The connecting wire from the spring contact member 60 runs to ground and also to one member of the push button while the wire of the other contact member 61 runs to the other member 110 of the push button and to the electro-mag- 115

120

125

130

- net. The other push button designated as B is in proper connection with the electro-magnet coil and with the lamp switch and of course it will be understood that the several parts are suitably insulated as required and properly electrically connected with the several parts, a detail description thereof not being deemed necessary of this very simple electrical organization.
- 10 From the foregoing it will be observed that when the magnet is energized by the operation of the push button B, the core or plunger 17 will be drawn backward from the contact member 21 while the spring 30 immediately acts through the pawl 27 to return the core to its contact position, thus insuring a make and break connection, so that the pawl moving with the core operates to rotate the ratchet wheel fixed to the shaft 20 23, and so rotate the eccentric and shift the reflectors from the point where they project the beam of light horizontally into a downward position to throw the rays of light downwardly and prevent the glare thereof.
- 25 The ratchet wheel is maintained against slipping backward by a suitable spring pawl 42 likewise carried by the bracket 15, so that the ratchet wheel can only move in one direction. During the movement of the reflector into its downward position, the fiber roll 62 is carried into position to engage the spring contact member 61, and when the reflector has been fully shifted downward this fiber roll, continuing its rotation with the eccentric and its shaft breaks contact between the member 60 and 61, and so disconnects as it were, the reflector from its operating means. In consequence the reflector cannot be shifted any farther either 35 40 downward or upward, and is therefore left in the position where it reflects all the rays of light downward on to the road and away from the eyes of an oncoming motor driver or pedestrian. In other words, operation of the push button B places the electric motor driving mechanism into operation to shift the reflector downward and when this has been accomplished the breaker mechanism disconnects the motor driving mechanism 45 50 55 60 65 70 75 80 85 90 95 100 105 110 115 120 125 130

contact member 61, and allowing it to return into contact with its member 60 and thus reestablish current to the motor.

From the foregoing it will be seen that I have provided what may be termed an effective locking means or blocking means for preventing the return movement of the reflector after it has been shifted downward until the operator also presses button A at the same time that button B is pressed. This is a very material advantage in devices of this kind, since when the reflector is shifted by pressing the button B, its continued movement in an upward or backward position is prevented in a positive manner and until the operator presses in addition to the button B the button A, whereas heretofore as in my prior case, the operator was likely to leave his finger too long upon the button or switch and thus carry the reflector immediately backward or upward to its normal position, and so at times unintentionally throw the light into the eyes of another motor driver.

It may be said in conclusion, that a practical demonstration has disclosed that the glare of oncoming headlights, so dangerous to motor drivers or oncoming pedestrians, is positively prevented when the light is shifted down on the road, while at the same time the light thrown on the road is sufficient to the full extent of such light a distance of from forty to one hundred feet ahead of the car. In other words, by means of the present improvement, the full force of the light is obtained ahead of the vehicle without cutting off any of it, while the dangerous glare so common in headlights, as now used, is entirely eliminated and in addition the disadvantage of the operator being able by accident to immediately throw the reflector back into its normal position is entirely avoided, requiring that this be done by a separate and distinct operation on the part of the operator.

It will be understood that the various details may be more or less changed without departing from the spirit or scope of the present improvement.

I claim as my invention:

1. A lamp comprising a casing, a shiftable reflector therein, means for shifting the reflector downwardly and upwardly, a pair of manually operative means for controlling said reflector shifting means, one effective to insure the movement of the reflector downwardly and the other co-operating to insure the movement of the reflector upwardly, and means for preventing the return movement of the reflector upwardly until both of said manually controlled means are simultaneously placed in operation.

2. A lamp comprising a casing, a shiftable reflector therein, electrically operative means located directly between the rear wall of the

When, however, it is desired to raise the reflector from its downwardly shifted position, it is necessary to press both button B and button A at the same time whereupon current is reestablished to the motor to place it in operation and thereby raise the reflector to its horizontal position, this carrying the eccentric away from the spring

shiftable reflector and the casing for shifting the reflector downwardly and upwardly, a pair of manually operative means for controlling said reflector shifting means, one effective to insure the movement of the reflector downwardly and the other coöperating to insure the movement of the reflector upwardly, and means for preventing the return movement of the reflector upwardly until both of said manually controlled means are simultaneously placed in operation.

3. A lamp comprising a casing, a shiftable reflector therein, means for shifting the reflector downwardly and upwardly, a pair of manually operative means for controlling said reflector shifting means, one effective to insure the movement of the reflector downwardly and the other coöperating to insure the movement of the reflector upwardly, and means carried by the casing and located directly between the rear wall of the shiftable reflector and the casing for preventing the return movement of the reflector upwardly until both of said manually controlled means are simultaneously placed in operation.

4. A lamp comprising a casing, a shiftable reflector therein, electrically operative means for shifting the reflector, and a make and break device located in the electrical circuit and automatically thrown into operation during the movement of the reflector for preventing movement of the reflector after it has reached a certain position.

5. A lamp comprising a casing, a shiftable reflector therein, electrically operative means for shifting the reflector, a make and break device located in the electrical circuit for preventing movement of the reflector after it has reached a certain position, and manually controlled means for restoring such electrical connection.

6. A lamp comprising a casing, a shiftable reflector therein, means for operating the reflector to shift the same downwardly and upwardly, means for controlling the downward movement of the reflector, means for controlling the upward movement thereof, and means for preventing the upward movement of the reflector until both of said means are put into simultaneous operation.

7. The combination of a lamp casing, a shiftable reflector therein, means for shifting said reflector and including electrical means comprising a shiftable plunger, and means located in the electrical circuit and automatically thrown into operation during the movement of the reflector for temporarily preventing the shifting of the reflector from a predetermined position.

8. The combination of a lamp casing, a shiftable reflector therein, means for shifting said reflector and including electrical means comprising a shiftable plunger, a pawl shifted by said plunger, a ratchet wheel

operated by said pawl, and means located in the electrical circuit and automatically thrown into operation during the movement of the reflector for temporarily preventing the shifting of the reflector from a predetermined position. 70

9. The combination of a lamp casing, a shiftable reflector therein, means for shifting said reflector and including electrical means comprising a shiftable plunger, a pawl shifted by said plunger, a ratchet wheel operated by said pawl, a spring for shifting the pawl and thereby the plunger in one direction, and means located in the electrical circuit and automatically thrown into operation during the movement of the reflector for temporarily preventing the shifting of the reflector from a predetermined position. 75

10. The combination of a lamp casing, a shiftable reflector therein, means for shifting said reflector and including a make and break electrically operative means, and a make and break device located in an electrical circuit for temporarily preventing shiftable movement of the reflector. 80 85

11. The combination of a lamp casing, a shiftable reflector therein supported for up and down tilting movement to prevent the glare of the lamp, means for shifting said reflector and including a make and break electrically operated means, a make and break device located in an electrical circuit for temporarily preventing shiftable movement of the reflector, and independent switches for controlling said make and break means, one at one time and both at another time. 90 95

12. The combination of a lamp casing, a shiftable reflector therein supported for up and down tilting movement to prevent the glare of the lamp, means for shifting said reflector and including a make and break electrically operative means comprising an electro-magnet, a shiftable core shifted by the magnet in one direction, spring controlled means for shifting the core in the opposite direction, and a make and break device located in an electrical circuit and automatically thrown into operation during the movement of the reflector for temporarily preventing shifting movement of the reflector. 100 105 110

13. The combination of a lamp casing, a shiftable reflector therein supported for up and down tilting movement to prevent the glare of the lamp, means for shifting said reflector and including a make and break electrically operative means comprising an electro-magnet, a shiftable core shifted by the magnet in one direction, spring controlled means for shifting it in the opposite direction, said spring controlled means comprising a pawl, a ratchet wheel operated by said pawl and connected with the reflector, and a make and break device located 115 120 125 130

in an electrical circuit for temporarily preventing shiftable movement of the reflector.

14. The combination of a lamp casing, a shiftable reflector therein supported for up and down tilting movement to prevent the glare of the lamp, means for shifting said reflector and including a make and break electrically operative means comprising an electro-magnet, a shiftable core shifted by the magnet in one direction, spring controlled means for shifting it in the opposite direction, said spring controlled means comprising a pawl, a ratchet wheel operated by said pawl and connected with the reflector, an eccentric, a shaft projecting into said ratchet wheel and also into the eccentric, and a make and break device located in an electrical circuit for temporarily preventing shiftable movement of the reflector.
15. The combination of a lamp casing, a shiftable reflector therein, means for shifting said reflector and including a make and break electrically operative means, a companion lamp casing also having a shiftable reflector, means extending from one casing to the other whereby the reflectors may be operated simultaneously by the same means which operates one of said reflectors, and means located in the electrical circuit and automatically thrown into operation during the movement of the reflector for temporarily preventing the shifting of both of said reflectors from a predetermined position.
16. The combination of a lamp casing, a shiftable reflector therein supported for up and down tilting movement to prevent the glare of the lamp, means for shifting said reflector and including a make and break electrically operative means, a companion lamp casing and shiftable reflector, means connecting the reflectors, whereby both may be operated by the same means which operates one of said reflectors, means located in the electrical circuit and automatically thrown into operation during the movement of the reflector for temporarily preventing the shifting of both of said reflectors from a predetermined position, and independent switches for controlling said make and break means, one at one time and both at another time.
17. The combination of a lamp casing, a shiftable reflector therein supported for up and down movement relatively to the road, electrically operative means for shifting said reflector and comprising a motor having a shiftable core, a pawl, said core and pawl having one a part projecting into the other, a ratchet wheel operated by said pawl, means connecting said ratchet wheel with the reflector, and means located in the electrical circuit for temporarily preventing the shifting of said reflector from a predetermined position.
18. The combination of a lamp casing, a shiftable reflector therein, an eccentric connected with the reflector, a shaft projecting into the eccentric, a ratchet wheel on said shaft for operating the eccentric, a pawl for operating the ratchet wheel, means for operating the pawl, and means for preventing the movement of the reflector when shifted into a certain position.
19. The combination of a lamp casing, a shiftable reflector therein, an eccentric connected with the reflector, a ratchet wheel for operating the eccentric, a pawl for operating the ratchet wheel, electrically operative means for operating the pawl, and electrically operative means for preventing the movement of the reflector when shifted into a certain position.
20. The combination of a lamp casing, a shiftable reflector therein, an eccentric connected with the reflector, a ratchet wheel for operating the eccentric, a pawl for operating the ratchet wheel, electrically operative means for operating the pawl and comprising an electro-magnet having a make and break shiftable core, a spring for shifting the pawl in one direction, and electrically operative means for preventing the movement of the reflector when shifted into a certain position.
21. The combination of a lamp casing, a shiftable reflector therein, an eccentric connected with the reflector, a ratchet wheel for operating the eccentric, a pawl for operating the ratchet wheel, electrically operative means for operating the pawl and comprising an electro-magnet having a make and break shiftable core, a spring for shifting the pawl in one direction, a pawl for preventing movement of the ratchet wheel in one direction, and electrically operative means for preventing the movement of the reflector when shifted into a certain position.
22. The combination of a lamp casing, a shiftable reflector therein, an eccentrically supported device connected with the reflector, a shaft projecting into the eccentric, means for operating said shaft and thereby the eccentrically supported device, and means for preventing movement of the reflector when shifted into a certain position.
23. The combination of a lamp casing, a shiftable reflector therein, means for shifting the reflector, and comprising an eccentrically supported device connected with the reflector, a ratchet wheel connected with the eccentric, a pawl for operating the ratchet wheel, an electro-magnet, a pair of make and break contact members, one having connection with the pawl and the other with the magnet, and means for preventing movement of the reflector when shifted into a certain position.
24. A lamp comprising a casing, a shiftable reflector therein, electrically operative

means for shifting the reflector into a tilted position and including a make and break device, means for preventing the movement of the reflector when shifted into said tilted position, and electrically operative means including said make and break device for effecting movement of the reflector to its original position.

25. The combination of a pair of head-light casings, a pair of reflectors pivotally supported therein, a connection between said reflectors at their open ends, electrically operative means for shifting said reflectors and including a make and break device, and
10 means automatically thrown into operation during the movement of the reflector for preventing movement of the reflectors when shifted to their downward position.

26. The combination of a pair of head-
20 light casings, a pair of reflectors pivotally
supported therein, an eccentric connected
with one only of said reflectors; a shaft pro-
jecting into said eccentric, a coupling con-
necting said reflectors adjacent to their open
25 ends, and means for operating said shaft
and thereby the eccentric and comprising
electrical mechanism located directly be-
tween the rear wall of the shiftable reflector
and its casing.

30 27. The combination of a pair of head-light casings, a pair of reflectors pivotally supported therein, an eccentric connected with one of said reflectors, a coupling connecting said reflectors adjacent to their open
35 ends, and means for operating said eccentric and comprising electrical mechanism including a make and break device for preventing movement of the reflectors when shifted into a downward position.

40 28. A lamp comprising a casing, a shiftable reflector located therein, and electrically operative means for shifting said reflector and including a pair of circuits and means for closing the same, one operative to shift the reflector into a downward position and jointly operative to return the reflector to its normal position.

29. A lamp comprising a casing, a shiftable reflector located therein, and electric

cally operative means for shifting said reflector and including a pair of circuits and means for closing the same, one operative to shift the reflector into a downward position and jointly operative to return the reflector to its normal position, said circuits including a make and break device operatively connected with the reflector for shifting it. 50 55

30. The combination of a lamp casing, a shiftable reflector therein supported for up and down tilting movement to prevent the glare of the lamp, means for shifting said reflector and including a make and break electrically operative means comprising an electro-magnet, a shiftable core shifted by the magnet in one direction, spring controlled means for shifting it in the opposite direction, said spring controlled means comprising a pawl, a ratchet wheel operated by said pawl and connected with the reflector by an eccentrically supported device, a make and break device, and means placed in operation on the rotation of the eccentric for breaking said device. 60 65 70

31. The combination of a lamp casing, a shiftable reflector therein, an eccentric connected with the reflector, a ratchet wheel for operating the eccentric, a pawl for operating the ratchet wheel, means for operating the pawl, and make and break mechanism comprising a pair of contact members and a rotating member, the latter rotatable with the eccentric for breaking contact between said contact members. 75 80

32. A lamp comprising a casing, a shift-
able reflector therein, electrically operative 85
means for shifting the reflector into a down-
ward position and including a switch, means
located in the electrical circuit for prevent-
ing the return of the reflector during the
continued operation of said switch and in-
cluding a make and break device, supple-
mental means for closing the circuit thereby
to throw out of operation the make and
break device and effect the return of the
reflector to its normal position. 90
